MECHANICAL LINKAGE

Alfred C. Hoven, Walter E. Nordmark, and William S. Lindberg, Grand Rapids, Mich., assignors to American Seating Company, Grand Rapids, Mich., a corporation of New Jersey

Application November 5, 1947, Serial No. 784,182

6 Claims. (Cl. 74—103)

1

The present invention relates to mechanical linkage whereby a member may be movably mounted on a fixed support therefor, and more particularly to provide such a mechanical linkage which is especially well adapted for use in chairs or the like having horizontally retractable seats and backs or vertically adjustable supporting pedestals, and this application is a continuation-in-part from our co-pending application for patent on Chair, Serial No. 767,992, filed August 11, 1947. The specific combination of the mechanical linkage herein claimed with a retracting type theater chair, as disclosed in Figures 4-7 of the drawings herein, is claimed in our co-pending divisional application Serial No. 148,228, filed March 7, 1950.

The primary objects of the invention are to provide a novel arrangement of pivotally connected links which, when mounted on a fixed supporting member, functions to support a movable member for guided movement relative to the fixed supporting member in an approximately straight path of movement; to provide such an arrangement of pivotally connected links which functions as stated irrespective of the direction of the said straight path of movement, and which may therefore be mounted at any selected angle on the fixed supporting member so as to support the movable member for guided movement in an approximately straight path in any direction desired; to provide such a mechanical linkage which is adapted to so support a movable member for movement in an approximately straight path and which also maintains the supported movable member at substantially the same predetermined angle of inclination during its movement relative to the fixed member; to provide a chair structure of the retracting type for use in theaters or the like, in which chair structure such a mechanical linkage is employed, in this application of which the linkage is mounted on the supporting standards for the chair and in turn provides a mounting for a chair seat in such a manner that the seat is movable rearwardly-downwardly and forwardly-upwardly in an approximately straight path and is maintained at substantially the same angle of forward-upward inclination during such movements, said linkage also providing a mounting for a chair back in such a manner that the back is movable rearwardly and forwardly with the seat and is angularly tilted during such movements so that when in its forward position the back is rearwardly-upwardly inclined and in its rearward position said back is substantially vertical; to provide such

2

a mechanical linkage adapted for general application to structures wherein one member is mounted on another for movement in a substantially straight path such, for example, as in a bus operator's chair wherein the seat and back unit is desirably mounted for vertical adjustment relative to a fixed supporting base therefor; and in general to provide such a mechanical linkage which is simple and rugged in construction and reasonably economical in manufacture.

These objects, and such other objects of the invention as will hereinafter become apparent are attained by, and the invention finds preferable embodiments in, the devices and structures hereinafter particularly described and illustrated in the accompanying drawings, wherein:

Figure 1 is a view, partially diagrammatic, of an arrangement of mechanical linkage, supporting means therefor, and other means supported thereby;

Figure 2 is a fragmentary view illustrating a variation or modification of the linkage shown in Figure 1;

Figure 3 is a view, partially diagrammatic, of another variation or modification of the mechanical linkage shown in Figure 1;

Figure 4 is a side elevational view of a theater or auditorium chair of the retracting type, employing the novel linkage of the present invention, the chair being here shown with the seat and back thereof in their forward or unstretched positions;

Figure 5 is a fragmentary front elevational view of the chair shown partly in section taken on the line 5—5 of Figure 4;

Figure 6 is an enlarged, fragmentary sectional view of parts of the chair, taken on line 6—6 of Figure 4;

Figure 7 is a side elevational view of the chair shown in Figure 4 with the seat and back thereof in their rearward, retracted, positions;

Figure 8 is a side elevational view, shown partly in section taken on line 8—8 of Figure 10, of a vertically adjustable chair of the general type used as operators' seats in motor buses or other vehicles, the seat here being shown in an elevated position relative to its fixed supporting base;

Figure 9 is a view similar to Figure 8 and showing the seat in a lowered position relative to its fixed supporting base; and

Figure 10 is a fragmentary sectional view of the same taken on line 10—10 of Figure 8.

Referring now in detail to Figure 1 of the drawings, the mechanical linkage there shown is

mounted on a fixed supporting member indicated by two fragments thereof both designated F₁ and F₂, it being understood that said fragments are fixed relative to each other. The linkage supports a movable member designated M for reciprocable movement in an approximately straight path indicated by the dotted line designated P extending between stations designated S₁ and S₂. A first or upstanding link designated 11 has its lower end pivotally connected to the 10 fixed supporting member at F near station S₁. A second or supporting link 12 of substantially the same effective length as the first link 11 has its upper end pivotally connected to the upper, free end of the first link 11 and has its lower end pivotally connected to the movable member M. A third or depending link 13 has its upper end pivotally connected to the fixed supporting member at F₂, near the travel path of the pivotal connection between the first and second links. A fourth or guide link 14 has one end thereof pivotally connected to the lower, free end of the third or depending link 13 and has its other end pivotally connected to the second link 12 and as here shown at the latter's point of pivotal connection to the movable member M. A fifth or connecting link 15 has its opposite ends pivotally connected to the first and third links 11 and 13 respectively, at points dividing these links in the following preferred proportion: The ratio of the third link's entire length A to that portion B thereof which lies between its connections to the fifth link and the fixed member, is approximately double the ratio of the first link's entire length C to that portion D thereof which lies between its connections to the fifth link and the fixed member. In equation form this relationship is expressed as follows:

$$\frac{A}{B} = 2 \times \frac{C}{D}$$

and the lengths may for example be as follows: A=7½ inches, B=2¼ inches, C=10 inches, and D=6 inches.

It will be seen that in the above arrangement, the lower end of the third link 13 is caused to move farther and faster than the upper end of the first link 11, and if the preferred proportions given in the above equation are adhered to, the third link's lower end travels exactly twice as far and twice as fast as the first link's upper end. Thus as the upper ends of the first and second links 11 and 12 move to the right (as viewed in Figure 1) through the positions 1-6 indicated on their arc of travel shown, the ends of the fifth or connecting link 15 also move to the right through corresponding positions 1-6 indicated on their arcs of travel shown, and the lower end of the third link 13 and that end of the fourth or guide link 14 to which the link 13 is connected are caused to move twice as far through positions 1-6 indicated on their arc of travel than do the upper ends of the first and second links 11 and 12 on their arc. The other end of link 14 (the right end as seen in Figure 1) being connected to the lower end of link 12, said lower end of link 12 is likewise urged toward movement twice as far and twice as fast as the upper end of said link 12. This is impossible however because such movement of the link 12 would tend to compress it during the first phase of the movement and to extend it during the last phase of said movement, and as a result the link 14 is constrained to change its angularity relative to the link 13. The angle between these links 13 and 14 thus

decreases during the first phase of the movement and increases during the last phase of said movement. As a result, the lower end of the second or supporting link 12 is constrained to movement in an approximately straight path as indicated by the dotted line P. Movement of the lower end of link 12 in the opposite direction is likewise constrained to said approximately straight path. It will thus be seen that between the stations S₁ and S₂ the movable member M can only move in an approximately straight path relative to the fixed supporting member.

In Figure 1 the movable member M, although it travels in an approximately straight path as shown, is free to rotate about its pivotal connection to the lower end of link 12. In Figure 2, the movable member M₂ has its rearward arm 26 pivotally connected to the lower end of link 22, which corresponds to the link 12 in Figure 1 and has an approximately straight path of movement as indicated by the dotted line P₂. The forward arm 27 of the movable member M₂ has a sleeve 28 slidably mounted on a rod 29 secured as by screws to lugs on the fixed supporting member shown fragmentarily at F₃ and F₄. Thus the movable member M₂ is mounted on the fixed supporting member for movement in an approximately straight path and is also maintained at substantially the same predetermined angle of inclination during its movement relative to the fixed supporting member. In this modification shown in Figure 2, the movable member M₂ is connected to the link 22 at a point below the pivotal connection between the links 22 and 24, instead of as shown in Figure 1, but the mode of operation is substantially the same. This modification shown in Figure 2 is similar to the disclosure in our above identified application of which this application is a continuation-in-part.

In Figure 3, links 31, 32, 33, 34 and 35 correspond to and operate the same as links 11, 12, 13, 14 and 15 respectively in Figure 1. In this modification shown in Figure 3, the upper end of link 31 is extended angularly beyond its pivotal connection to the upper end of link 32, and a sixth link 36 is pivotally connected to the extension 37 of the link 31 and depends therefrom. The forward portion of the movable member M₃ is pivotally connected to the lower end 50 of the sixth link 36, said pivotal connection being in substantial alignment with the pivotal connection of the movable member M₃ to the lower end of link 32 and with the pivotal connection of the link 31 to the fixed supporting member F₅. The rearward end of the movable member M₃ is guided in an approximately straight path P₃ identical to the path P of Figure 1 and shown in dotted line, while the forward end of the movable member M₃ is guided in a curved path P₄ shown in broken line, the curvature of said path P₄ being so slight that the path P₄ is roughly coincident with and an extension of the path P₃. The movable member M₃ is thus mounted solely by mechanical linkage on the fixed supporting member F₅, F₆, for movement in an approximately straight path and is also maintained at substantially the same predetermined angle of inclination during its movement relative to the fixed supporting member.

The retracting-type theater chair shown in Figures 4-6 employs linkage identical to that shown in Figure 3 for mounting a chair seat 38 and chair back 39 on spaced, upright standards 40 which form the fixed supporting frame for the chair and which correspond to the fixed support-

ing member F5, F6 of Figure 3. The mountings at opposite sides of the chair are preferably identical. Upstanding links 41, rear supporting links 42, depending links 43, guide links 44 and connecting links 45 correspond to and operate the same as links 11, 12, 13, 14 and 15 respectively of Figure 1 and the same as links 31, 32, 33, 34 and 35 respectively of Figure 3. Front supporting links 46 and seat carriers 47 correspond to and operate the same as link 36 and movable member M3 respectively of Figure 3. The chair seat 38 is mounted on the seat carriers 47 as by means of hinge members 48 secured to the seat carriers by screws 49 and having hinge pins 50 on which the seat is mounted turnably to raised and lowered positions. If desired, this hinge structure may include spring means (not shown) for normally maintaining the seat in a raised position.

The chair back 39 is mounted upon the rear supporting links 42 and is movable therewith, being secured thereto at the pivotal connections 51 between the rear supporting links 42 and the upstanding links 41, and also being secured thereto by means of rivets 52.

It will be seen that as the chair is retracted by an occupant thereof in order to permit others to pass in front of him, the seat 38 moves rearwardly in a substantially straight downwardly-inclined path and that it is maintained at substantially the same predetermined angle of inclination, while the back 39 moves rearwardly and tilts from its rearwardly-upwardly inclined position shown in Figure 1 to its substantially vertical position shown in Figure 3. Rearward movement of the seat and the back is stopped by contact of the upper ends of the links 41 with stops 53 on the standards 40, while forward movement of the seat and the back is stopped by contact of the seat carriers with stops 54 on the standards. It will be apparent that many other means for stopping these forward and rearward movements might be contrived and such means, or the stops 53 and 54 shown, may if desired be equipped with cushioning and silencing rubber bumpers (not shown). Also not shown in the drawings is means for shielding the linkage from the chair occupant, but a convenient method of accomplishing this is to extend the side portions 55 of the sheet metal back forwardly and flange them outwardly to form housings for the mechanisms.

The retracting chair described above is especially well adapted for installation in either straight rows of chairs or in curved rows wherein the common supports for adjoining chairs, or "middle standards" as they are called, converge slightly inwardly toward the front, the long links 41, 42, 43 and 46 providing the necessary flexibility for such installation in curved rows. This flexibility is also useful in compensating for inaccuracies in the placement of the standards. In order to prevent undesirable side play in the seat and back, there is preferably provided a guide at one side or if desired at both sides of the chair. The guide shown comprises an extension 56 on the seat carrier 47 which projects downwardly, then outwardly, and then upwardly into an inverted U-shaped channel or guideway 57 secured to the adjacent standard 40 at the front and rear as by rivets 58. The portion of the seat carrier's extension 56 which extends upwardly into the guideway 57 may desirably have oppositely stamped semi-spherical embossings 59 which insure a smooth bearing of the guide against the side walls of the guideway 57 with a minimum of friction, and a lubricant may if 75

described be applied to the inside of the guideway. It will be particularly noted that the guide and guideway here described bear none of the weight of the chair or the occupant thereof, but serve as guides alone. The weight of the chair seat and back and of the occupant thereof are supported entirely by the mechanical linkage mounted on the standards and hereinbefore described.

10 Figures 8-10 disclose a chair of the vertically adjustable type adapted for installation in motor busses or other vehicles for occupancy by the drivers thereof. The chair generally comprises a fixed supporting member or base 60 upon which is mounted a mechanical linkage comprising links 61, 62, 63, 64, 65 and 66 which correspond to and operate the same as the links 31, 32, 33, 34, 35 and 36 respectively of Figure 3, except that the linkage here shown provides a vertical movement in a substantially straight path for a movable member or bracket 67 mounted on the rearward ends of links 62 and 66. A chair frame 68 is mounted on the bracket 67 and carries a chair seat 69 and back 70. In this application of the invention, the duplicate mechanical linkages at opposite sides of the chair are connected by a web 71 secured to or integral with the pair of links 61 and a web 72 secured to or integral with the links 66, and this arrangement lends rigidity to the structure. A strong tension spring 73 normally urges the bracket 67 and the chair mounted thereon in an upwardly direction to facilitate vertical adjustment of the chair without the necessity of lifting these parts. A foot pedal 74 pivotally mounted on the base 60 may be depressed as indicated by the dotted lines of Figure 8 by the chair occupant, thus disengaging detents 75 from racks 76 on the forward end portions of links 61 and permitting the chair to descend 40 under the weight of the occupant. The occupant may then by shifting his weight adjust the chair to the desired height and release the foot pedal 74, whereupon a pair of compression springs 77 return the detents 75 into engagement with the racks 76 and the chair is thus secured in vertically adjusted position.

It will thus be seen that the present invention provides a novel mechanical linkage which is adaptable to structures wherein a movable member is mounted on a fixed supporting member therefor in such a manner that the movable member is guided in a preselected substantially straight path of movement while at the same time said movable member is maintained at substantially the same predetermined angle of inclination relative to the fixed supporting member; that a theater chair of the retracting type is provided which is smooth in operation, flexible to meet varying conditions of installation, sturdy in construction and attractive in appearance; and that a chair of the vertically adjustable type is provided which is smooth in operation, sturdy in construction and reasonably economical in manufacture.

The invention being intended to be pointed out in the claims, it is not to be limited to or by details of construction of the particular embodiments thereof shown in the accompanying drawings or hereinbefore described.

We claim:

1. Mechanical means for mounting a movable member on a fixed supporting member therefor in such a manner that said movable member is guided in an approximately straight path of movement between predetermined first and

second station points on the fixed supporting member; said means comprising: a first link having one end thereof pivotally connected to the fixed member at the first station point thereon and extending therefrom at an acute angle to said path of movement; a second link of the same length as the first link having one end thereof pivotally connected to the free end of the first link and the other end thereof connected to the movable member and movable along said path of movement between the first and second station points on the fixed member; a third link having one end thereof pivotally connected to the fixed member at a point near the travel path of the pivotal connection between the first and second links and having its other end swingable in an arc in proximity to the path of movement between said first and second stations; a fourth link having one end thereof pivotally connected to the free end of the third link and its other end connected to the second link near the latter's connection to the movable member; and a fifth link having one end thereof pivotally connected to the first link and the other end thereof pivotally connected to the third link, the ratio of the third link's entire length to that portion thereof which lies between its connections to the fifth link and the fixed member being approximately double the ratio of the first link's entire length to that portion thereof which lies between its connections to the fifth link and the fixed member.

2. Mechanical means for mounting a movable member on a fixed supporting member therefor in such a manner that said movable member is guided in an approximately straight path of movement between predetermined first and second station points on the fixed supporting member, said means comprising: a first link having one end thereof pivotally connected to the fixed member at the first station point thereon and extending therefrom at an acute angle to said path of movement; a second link of the same length as the first link having one end thereof pivotally connected to the free end of the first link and the other end thereof connected to the movable member and movable along said path of movement between the first and second station points on the fixed member; a third link having one end thereof pivotally connected to the fixed member at a point near the travel path of the pivotal connection between the first and second links and having its other end swingable in an arc in proximity to the path of movement between said first and second stations; a fourth link having one end thereof pivotally connected to the free end of the third link and its other end connected to the second link near the latter's connection to the movable member; and a fifth link having one end thereof pivotally connected to the first link and the other end thereof pivotally connected to the third link, said pivotal connections of the fifth link to the first and third links being such that the free end of the third link travels approximately twice as far as the free end of the first link.

3. Mechanical means for mounting a movable member on a fixed supporting member therefor in such a manner that said movable member is guided in an approximately straight path of movement between predetermined first and second station points on the fixed supporting member, said means comprising: a first link having one end thereof pivotally connected to the fixed member at the first station point thereon and extending therefrom at an acute angle to said path

of movement; a second link of the same length as the first link having one end thereof pivotally connected to the free end of the first link and the other end thereof connected to the movable member and movable along said path of movement between the first and second station points on the fixed member; a third link having one end thereof pivotally connected to the fixed member at a point near the travel path of the pivotal connection between the first and second links and having its other end swingable in an arc in proximity to the path of movement between said first and second stations; a fourth link having one end thereof pivotally connected to the free end of the third link and its other end connected to the second link near the latter's connection to the movable member; and a fifth link having one end thereof pivotally connected to the first link and the other end thereof pivotally connected to the third link, said pivotal connections of the fifth link to the first and third links being such that the free end of the third link travels farther than the free end of the first link.

4. Mechanical means for mounting a movable member on a fixed supporting member therefor in such a manner that said movable member is guided in an approximately straight path of movement between predetermined first and second station points on the fixed supporting member, said means comprising: a first link having one end thereof pivotally connected to the fixed member near the first station point thereon and extending therefrom at an acute angle to said path of movement; a second link of substantially the same length as the first link having one end thereof pivotally connected to the free end of the first link and the other end thereof connected to the movable member and movable along said path of movement between the first and second station points on the fixed member; a third link having one end thereof pivotally connected to the fixed member at a point near the travel path of the pivotal connection between the first and second links and having its other end swingable in an arc in proximity to the path of movement between said first and second stations; a fourth link having one end thereof pivotally connected to the free end of the third link and its other end connected to the second link near the latter's connection to the movable member; and a fifth link having one end thereof pivotally connected to the first link and the other end thereof pivotally connected to the third link, said pivotal connections of the fifth link to the first and third links being such that the free end of the third link travels farther than the free end of the first link.

5. Linkage mounted on a fixed member at two spaced points, comprising: a first link pivotally connected to the fixed member at the first of said points and having its free end swingable in proximity to the second of said points; a second link pivotally connected to the free end of the first link and having its free end movable in an approximately straight path intersecting the first of said points; a third link pivotally connected to the second of said points and having its free end swingable in an arc having its ends near the ends of said approximately straight path; a fourth link connecting the free ends of the second and third links; and a fifth link connecting the first and third links so as to accelerate the movement of the third link's free end relative to the movement of the first link's free end thus constraining the movement of the connection between the

second and fourth links to said approximately straight path.

6. Mechanical means for mounting a movable member on a fixed supporting member therefor in such a manner that said movable member is guided in an approximately straight path of movement between predetermined first and second station points on the fixed supporting member, said means comprising: a first link having one end thereof pivotally connected to the fixed member at the first station point thereon and extending therefrom at an acute angle to said path of movement; a second link of the same length as the first link having one end thereof pivotally connected to the free end of the first link and the other end thereof connected to the movable member and movable along said path of movement between the first and second station points on the fixed member; a third link having one end thereof pivotally connected to the fixed member at a point near the travel path of the pivotal connection between the first and second links and having its other end swingable in an arc in proximity to the path of movement between said first and second stations; a fourth link having one end thereof pivotally connected to the free end of the

third link and its other end connected to the second link near the latter's connection to the movable member; a fifth link having one end thereof pivotally connected to the first link and the other end thereof pivotally connected to the third link, said pivotal connections of the fifth link to the first and third links being such that the free end of the third link travels farther than the free end of the first link; and a sixth link having one end thereof pivotally connected to the first link near its free end and having the other end thereof connected to the movable member at a point spaced from the connection between the movable member and the second link.

ALFRED C. HOVEN.
